WEAR ACCESSORY

Paul Marx and Artie Abraham, New York, N. Y.

Application May 23, 1946, Serial No. 671,849

10 Claims. (Cl. 2—132)

1

The invention relates to a wear accessory, and more in particular, to a pin clip attachable to a garment for a variety of uses. Although, in one of its forms, primarily intended to serve as a collar holder to keep the edges of a shirt collar in desirable shape and to prevent the collar points from bending, the invention aims in general to provide a pin clip which is substantially secure against accidental loosening, which has stiffening qualities, and in which the pin point or points are covered to minimize the danger of injuring the wearer. Another object of the invention is to provide a pin clip which will not tilt or turn but will stay flat, that means substantially parallel to the plane of the garment to which it is attached, and which thus is also advantageously useful as a bar for medal ribbons or as an insigne of a uniform, and in a decorated or ornamented form, as a brooch or costume jewelry, or as a pin or clip for many other purposes.

If used as a collar stiffener or holder the device according to the invention comprises two elongated pin clips, one to be attached to each collar edge, the two pin clips being connected by a relatively short flexible member at points intermediate their ends to limit the space the two collar edges can spread apart. In its preferred form, the individual clip comprises an elongated casing with a lower wall shorter than the upper wall and with prongs therebetween and extending beyond the lower wall at the opposite ends of the casing, at least one of the prongs being retractable against the restraint of a spring.

Further objects and details of the invention will be apparent from the description given hereinafter and the accompanying drawing illustrating embodiments thereof by way of example.

In the drawing,

Fig. 1 is a front elevation of an embodiment of my invention,

Fig. 2 is a similar view of another embodiment,

Fig. 3 is a perspective view of one of the pin clips shown in Fig. 2, at a larger scale,

Fig. 4 is a cross-section along line 4—4 of Fig. 3,

Fig. 5 is a section along line 5—5 in Fig. 4,

Figs. 6, 7, and 8 are sections along the lines

6—6, 7—7, and 8—8, respectively, of Fig. 5.

Fig. 9 is a perspective view of a modified clip,

Fig. 10 is a bottom plan view thereof, the bottom part of the casing being removed,

Fig. 11 is a longitudinal cross-section of a portion of the clip of Fig. 9, and

Fig. 12 is a cross-section along line 12—12 of Fig. 11.

Referring now to the drawing, Fig. 1 shows our

2

invention in use as a collar stiffener and holder. The device comprises two elongated members 1 of substantially rigid character, which are connected by a flexible element 2. The members may be shaped similar to a safety pin, that means with a pin or pricking portion 3, a resilient bend 4, a back 5 and a hook or catch 6. Intermediate their ends, the backs 5 are provided each with a means, for instance a loop 7, to which the ends of the flexible element 2, shown as a little chain, are fastened. When the pins are attached, preferably to the inside of and substantially parallel to the edges 8 of a collar 9, their rigidity will lend the desired stiffness to the edges and the chain or other flexible element will prevent the edges from spreading unduly apart. If this element is positioned underneath the tie 10, the entire device will be concealed, and the element 2 may even push the tie somewhat outward for a very neat appearance.

The very simple form of the described collar stiffener and holder according to our invention is improved in the preferred form illustrated in Figs. 2 to 8. Whereas the members 1 can tilt about their pin portions, means are provided in the embodiment which will now be described to insure that the pin clip or clips stay flat when attached. By other means it is also attained that the bend of the upper rim of the collar 30 where it is turned down, is supported for a correct and lasting fit. The embodiment of Fig. 2 consists, as in the first described form, of two pin clip members connected by a flexible element. Each pin clip comprises a casing in general denoted by 11 and shaped of a lower and an upper elongated member 12 and 13 respectively as clearly shown in Figs. 3 to 8. The lower member 12 is so bent or otherwise formed, preferably of sheet metal, that it constitutes a flat bottom wall 14 and two upright side walls 15, 16 with inward directed flanges 17 and 18, respectively. The upper member 13 is a substantially flat strip of sheet metal fitting between the side walls 15, 16 and under the flanges 17, 18. It 45 may be stiffened by being pressed, for instance in roof-like shape as shown at 19, over its total length or part thereof. Although we have mentioned metal as the preferred material for the casing, other materials, such as a plastic, may be used if so desired. The upper member is longer than the lower member and projects a distance from both ends of the latter at 20 and 21. Depending on the purpose for which the clip is intended, one or both ends of the upper member 50 may be provided with an extension. In the illus-

trated embodiment such extension 22 of the end 21 is bent back at an angle to the casing and provided with a button 23 for a purpose to be explained hereinafter. If there is no such extension, button 23 may be directly secured to another portion of the upper member 13, for instance to or near the end portion 21. In several places, pairs of incisions 24 are made in the side edges of the upper member and the material between the incisions is bent downward to form spacers, abutments and/or guides 25, 26, 27, 28, and 29. All these portions 25 to 29 are so long that they bear on the lower wall 14 as clearly shown in Fig. 6, thereby insuring that member 13 bears against the lower sides of the flanges 17, 18. A U-shaped two-pronged pin 30, preferably of resilient material is so positioned in casing 11 that the prongs 31 and 32 are held, the one between side wall 15 and abutment 28, and the other one between side wall 16 and abutment 29. The pointed ends 33 and 34 of the prongs are slightly bent downward and project from the lower casing member 12 but are covered or overlapped by the upper member portion 21. The portion 35 of the pin, connecting the two prongs, is secured to the upper casing member 13 for instance by soldering or welding as indicated at 36. A similar two-pronged pin 37 is arranged at the opposite end of the casing. This pin is movable in the longitudinal direction of the casing and guided by the side walls 15, 16 of the latter and the abutment or guide portions 25 and 26. The middle portion 38 of the pin is provided with an upward projection 39 which may be welded or otherwise secured thereto and protrudes through a slot 40 in the upper casing member 13. Slot 40 is so dimensioned that its one end, i. e. the left-hand end in Fig. 3 constitutes an abutment for projection 39 so as to limit an outward movement of the pin 37 to a position analogous to that of the fixed pin 30, that means a position in which the prong ends are still but very slightly overlapped by the end 20 of the upper casing member 13. A spring is provided, tending to urge the pin 37 into such position. In order to make casing 11 as flat as possible, a zig-zag spring 41 is used in the illustrated embodiment and so arranged that it bears with its one end against the portion 38 of pin 37 and with its other end against the abutment 27.

Owing to the described structure, the parts can be readily assembled by first securing pin 30 to the member 13, then, while the latter is held upside down, positioning the pin 37 and spring 41 in correct relationship thereto, and finally sliding the lower member 12 on the upper member 13 from the one end thereof. In order to apply the clip, it is gripped between thumb and index finger of one hand, engaging the button 23 and projection 39 and thereby retracting pin 37. The prong ends 33 and 34 of the fixed pin are first inserted in the fabric to which the clip is to be attached; then the other end of the clip is brought down on that fabric. When, now the projection 39 is released, the slightly downward directed points of pin 37 will also enter into the fabric while the pin is projected by spring 41. It will be clear that the clip so affixed is practically secure against accidental loosening, and that the casing acts as a stiffener of the fabric material gripped between the pins. Furthermore, owing to the overlap of the upper casing member and owing to the fact that the pin points do not project outwards of the fabric, injuries by these points are practically excluded.

Although we have shown twin-pronged pins in the illustrated embodiment, single-pronged pins may be used with results similar to those mentioned. However, the double-pronged pins offer the further advantage that the clip will not tilt about its longitudinal axis as it may do in the case of single-pronged pins.

In the form of the collar stiffener and holder of Fig. 2, the two clips, in general denoted by 10 and 42 and 43, are connected by the chain or other flexible member 44 which is attached to the clip buttons 23. The clips may be attached to a collar in a similar arrangement to that stated with respect to the embodiment of Fig. 1, so however, that the bend of the extension 22 engages into the bend of the upper collar rim to insure a correct shape. The buttons 23 and chain 44 will, then, also be in a suitable position to prevent the edges 8 of the collar 9 from spreading beyond a fitting distance. If it is desired, to wear the clips with an open shirt, the chain 44 may be removed, the clips, then, preventing the collar points from bending upward.

Similarly, a single clip of the form of Fig. 3 may be used for other purposes, in which event some other article, as for instance a watch or a pince-nez may be suspended from the hook shaped extension 23. If, on the other hand, the pin clip is used for still other purposes, as mentioned above, the extension may be omitted. A clip without extension is illustrated in Figs. 9 to 12, which show also certain modifications in other respects.

The modified clip comprises a lower casing member 102 similar to that denoted by 12 in Fig. 3. The upper casing member 103 is a straight strip bent into roof-shape 104 throughout its length. Its ends 105 and 106 project from the lower member so as to overlap the pronged pins 107 and 108 which are positioned at opposite ends in the casing formed by the members 102 and 103. Whereas, however, in the first embodiment only the pin 37 is shiftable, both the pins 107 and 108 may be retracted by hand and projected by resilient means. Furthermore, whereas there is a projection 39 directly secured to pin 37 as a means for retracting it, a slide 109 shiftable within the casing is provided with a projection 110 which is passed through a slot 111 in the casing wall, be it in the side wall of the lower member or, as shown, in the top of the upper member 103. This projection may either be an integral portion of the slide or may be a piece secured to the slide as e. g. a small screw shown in Fig. 11. Pin 107 is secured to the slide for instance by welding or soldering as indicated at 112 and a spring 113 which may have any suitable form bears against the other side of the slide. For the reasons stated hereinbefore, a spring of zig-zag shape is preferred in the clip according to the invention. The slide 109 is, furthermore, provided with an extension 114 located between the upper member 103 and spring 113. The extension is of such a form and length that it overlaps the slot 111 from the inside of the casing to conceal the spring when the clip is used. Pin 108 is secured to a slide 115 of a shape similar to that of the slide 109. The projection 116 of slide 115 is passed through another slot 117 of the casing, so that the pin can be retracted from its adjacent casing end against the restraint of a resilient means bearing on the slide 115. Such resilient means may be separate from the spring acting on pin 107. However, it is preferred to

provide only one spring 113 interposed between both the slides 109 and 115 as clearly shown in Fig. 10. Although this is not necessary as far as the action of the spring is concerned, abutments 118 and 119 may be provided on the upper casing member to hold the middle portion of the spring in position. In all other respects, the clip of Fig. 9 is similar to that of Fig. 3, and it will be clear that features described with respect to the one clip may be applied to the other and vice versa.

It will be apparent to those skilled in the art that many alterations and modifications of the illustrated embodiments are possible without departure from the spirit and essence of our invention which, for this reason, shall not be limited but by the scope of the appended claims.

We claim:

1. A clip comprising an elongated, open-ended casing having a lower and an upper wall portion, the upper wall portion protruding beyond the lower at both ends of the casing, two pins located partly in the interior of the opposite casing ends, respectively, and projecting therefrom with their points so that the points are free from said lower wall but overlapped by the upper, at least one of said pins being lengthwise shiftable, a spring interiorly of the casing and biasing said shiftable pin, means accessible from the outside and connected to said shiftable pin to retract the latter against the restraint of said spring, and an abutment to prevent projection of said pin beyond a predetermined limit.

2. A clip as claimed in claim 1, the points of said pins being slightly turned downward approximately to the level of the bottom surface of the lower casing wall.

3. A clip as claimed in claim 1, each of said pins having a plurality of prongs in a plane substantially parallel to the lower surface of said casing.

4. A clip as claimed in claim 1, wherein one of said pins is rigidly secured to said casing, the pointed end of said pin projecting from the end of the lower casing wall a distance similar to that the shiftable pin projects from the opposite end of the lower casing wall when stopped by said abutment.

5. A clip as claimed in claim 1, wherein both said pins are shiftable, said spring being arranged between said pins so as to urge the latter in opposite directions.

6. A clip as claimed in claim 1, the upper wall portion including an extension at one of its ends, said extension being bent back at an angle upon said casing, and embodying means for the attachment of an extraneous element.

7. A pin clip device as a collar stiffener or the like comprising a pair of clips, each clip comprising an elongated open-ended casing having a lower and an upper wall portion, the upper wall portion protruding beyond the lower at both ends of said casing, two pins located partly in the interior of the opposite casing ends, respectively, and projecting therefrom with their points which are overlapped by the ends of said upper wall portion, one of said pins being lengthwise shiftable, a spring interiorly of said casing and bear-

ing against said shiftable pin, means accessible from the outside and connected to said pin to retract the latter against the restraint of said spring, an abutment to prevent projection of said pin beyond a predetermined limit, said other pin being rigidly connected to said casing, the upper wall portion including an extension at its end adjacent said rigidly secured pin, said extension being bent back at an angle upon said casing, and a flexible member connecting the free ends of the extensions of both said clips.

8. A clip comprising an elongated, substantially flat and open-ended casing having a lower and an upper wall, the upper wall protruding beyond the lower at both ends of the casing, two two-pronged pins located partly in the interior of the opposite casing ends, respectively, and projecting therefrom with their points so that the latter are free from said lower wall but permanently overlapped by the upper wall, at least one of said pins being lengthwise shiftable, a flat zig-zag spring interiorly of said casing and tending to project said pin, means accessible from the outside and movable with said shiftable pin to retract the latter against the restraint of said spring, and an abutment to prevent projection of said shiftable pin beyond a predetermined limit.

9. A clip as claimed in claim 8, said casing comprising a lower member embodying said lower wall, and an upper member embodying said upper wall, said lower member having a substantially U-shaped cross-section with inwardly bent flange portions, said upper member having side edges engaging with their upper faces said inwardly bent flange portions of said lower member and having downwardly bent portions located between the prongs of each pin and constituting spacers to insure clearance between said members for the reception of said pins and said spring.

10. A clip as claimed in claim 8, further comprising a slide interiorly of said casing between said shiftable pin and said spring, said shiftable pin being rigidly secured to said slide, said spring bearing against said slide, a projection of said slide protruding outward through a longitudinal slot of a wall portion of said casing, and an extension of said slide overlapping said slot on the inside of the casing when the slide is in a position in which said shiftable pin is projected.
